UNITED STATES PATENT OFFICE.

THOMAS JAMES FLYNN, OF PHILADELPHIA, PENNSYLVANIA, ASSIGNOR TO THOMAS POTTER, SONS & COMPANY, INCORPORATED, OF PHILADELPHIA, PENNSYLVANIA.

MANUFACTURE OF INLAID LINOLEUM FLOOR-CLOTH.

SPECIFICATION forming part of Letters Patent No. 690,053, dated December 31, 1901.

Application filed July 13, 1900. Serial No. 23,531. (No model.)

To all whom it may concern:

Be it known that I, THOMAS JAMES FLYNN, a resident of Philadelphia, in the county of Philadelphia and State of Pennsylvania, have ⁵ invented certain new and useful Improvements in the Manufacture of Inlaid Linoleum Floor-Cloth, of which the following is a specification.

This invention comprises improvements ¹⁰ having as their objects the reduction of the cost of manufacture by a simplified and rapid mode of operation through which the variously-colored tesserae required to form the design may be given a granite-like appearance and a pattern of perfect symmetry with clearly-defined lines between the tesserae ¹⁵ may be formed in contrast to the former irregular blending of the variously-colored tesserae. These ends are attained by pressing the linoleum composition of the various colors required for the design in molds adapted for the independent formation of tesserae of perfect symmetry and sufficient density to be ²⁰ readily handled. The shapes thus molded, independently of the operation of securing them to the backing, may be given a degree ²⁵ of symmetry which insures their perfect registration when assembled in forming the design, and the final pressure employed for ³⁰ curing their attachment to the backing expands them sufficiently to form fine straight lines of juncture without blending.

In practicing the invention the molded tesserae may be arranged upon the backing either ³⁵ by hand, by means of templets, or the plungers employed for consolidating the composition into tesserae may be used to effect their removal from the molds and their attachment to the canvas backing. By securing greater ⁴⁰ adhesive force between the molded tesserae and the plungers employed in forming them than exists between the tesserae and the mold-cells in which they are formed the tesserae are readily removed from the molds by the ⁴⁵ withdrawal of the plungers to which they adhere and may be directly transferred in proper order and attached to the backing by means of the plungers. I have found that the operation of withdrawing the tesserae

from the molds may be effected by employing plungers with zinc faces and molds with oiled or very smooth surfaces. The withdrawal of the tesserae from the molds may be effected otherwise, as by means of plungers having roughened surfaces or surfaces having ⁵⁰ small pins projecting therefrom.

The accompanying drawings illustrate mechanism adapted for practicing my improvements, in which—

Figure 1 is a transverse sectional elevation ⁶⁰ of a molding device. Fig. 2 is a sectional plan view on the line *a a* of Fig. 1. Fig. 3 is a sectional elevation on the line *b b* of Fig. 1. Fig. 4 is a perspective view of a form of the product. Fig. 5 is a longitudinal sec- ⁶⁵ tional elevation illustrating further apparatus for the practice of the invention; and Fig. 6 is a plan view of the construction illustrated in Fig. 5, part being shown in section, taken on the line *c c* thereof. ⁷⁰

The mode of operation, as illustrated by Figs. 1 to 4, inclusive, comprises charging linoleum composition, preferably granulated and variegated by mixing, into a molding-box 1, containing the molding-frame 2, having its face divided into cells 3, the box providing sufficient space for receiving the quantity of loose composition required for filling the cells and forming the tesserae when consolidated by the action of the plunger 4. To ⁸⁰ permit the ready withdrawal of the consolidated tesserae from the cells and to facilitate the construction of the design upon the backing to which they are finally attached, the cells are preferably inverted pyramidal frus- ⁸⁵ tra in contour; but this is not essential to the operation. The composition having been consolidated and formed into tesserae within the cells 3, (as by the use of hydraulic jacks, as ⁹⁰ 5, having a platen 6, which force the mold upward against the plunger 4 held by the press-head 7,) the mold and plunger are moved along the track 8 upon the wheels 9, secured to the frame, until clear of the press. The plunger is then lifted out of the molding- ⁹⁵ box by means of the bosses 10 thereon, and the shapes adhering to the face 11 thereof are removed from the cells thereby. These tes-

seræ may be detached from the face of the plunger and arranged upon the backing in any suitable manner to form a product of such character as is illustrated in Fig. 4.

5 The mode of operation as practiced by the mechanism illustrated in Figs. 5 and 6 employs molds, as 12, having cells 13 of the form required for one figure of the pattern and arranged as that figure is to be arranged in the 10 pattern. These cells are filled with composition of the required color, which is consolidated into tesserae by means of the plungers 14, the mold being forced upward by jacks, such as 15, against the plungers, whose body 16 impinges against and is held by the press-heads 17. The tesserae having been formed and the jacks lowered, thus lowering the mold, the tesserae are withdrawn from the cells by 20 adhering to the faces 18 of the plungers, which are prevented from falling by the wheels 19 on the body thereof, which rest upon the track 20. These plungers, with the tesserae adhering thereto, may now be moved forward upon the track to a definite position under the press-heads 21 and over the platen 22, elevated by jacks, as 23. The canvas backing 24, drawn 25 from the roll 25 over the roller 26 and between the platen and the plungers, receives the tesserae, which are caused to adhere thereto by forcing the platen 22 upward through the action of the jacks upon which it is supported. When the platen is lowered, the tesserae composition having penetrated the meshes of the canvas has greater adhesion 35 therefor than for the plungers, from which they may now be separated while continuing to adhere to the canvas. The canvas, with the ground-figure of the design fixed thereon, may now be moved forward upon the table 40 27, where the remaining figures may be filled in manually; but all of the figures of the design may be placed upon the backing mechanically by duplicating the molds and plungers shown, with such changes in form as the various shapes require and by lengthening the 45 track to permit the operation of such duplicate parts. The tesserae forming the complete design having been arranged upon the backing section by section, as described, they 50 are finally consolidated by passing them between the press-head 28 and the platen 29, operated by jacks, as 30.

It will be understood that the mechanism which I have illustrated and described may be varied or supplemented by additional mechanism without departing from the principle of my invention—as, for instance, the employment of a stationary mold 12 and a stationary platen 22 for coöperation with any suitable means for moving the plungers 14 vertically in the operation of consolidating the composition within the mold and of fixing the tesserae upon the backing.

Having thus described my invention, I claim—

1. The mode of making inlaid linoleum floor-cloth which consists in molding linoleum composition into independent tesserae, subsequently arranging said molded tesserae upon a woven backing, and finally pressing said 70 tesserae upon said backing until the composition penetrates the meshes of said backing, substantially as specified.

2. The mode of making inlaid linoleum floor-cloth which consists in molding granulated linoleum composition into independent tesserae of clearly-defined outline and of sufficient density to permit them to be handled, then arranging said tesserae upon a backing, and finally pressing said tesserae upon said 80 backing, substantially as specified.

3. The mode of making inlaid linoleum floor-cloth which consists in mixing different colors of granulated linoleum composition, molding said mixed granulated composition into independent tesserae of clearly-defined outline and of sufficient density to permit them to be handled, arranging said tesserae upon a backing, and finally pressing said tesserae upon said 85 backing, substantially as specified.

4. The mode of making inlaid linoleum floor-cloth which consists in molding adhesive linoleum composition into independent tesserae, transposing said tesserae to a backing by means of their adhesive condition, and finally 90 pressing said tesserae upon said backing, substantially as specified.

In testimony whereof I have hereunto signed my name, this 10th day of July, 1900, in the presence of the subscribing witnesses.

THOMAS JAMES FLYNN.
